UNITED STATES PATENT OFFICE.

LUDWIG SINGER, OF BOCHUM, GERMANY.

AUTOMATIC CHARGING DEVICE FOR ROASTING-FURNACES AND THE LIKE.

1,071,962.

Specification of Letters Patent. Patented Sept. 2, 1913.

Application filed March 22, 1913. Serial No. 756,064.

To all whom it may concern:

Be it known that I, LUDWIG SINGER, a subject of the King of Hungary, and resident of 51² Gemeindestrasse, Bochum, in the 5 Kingdom of Prussia, Empire of Germany, manager, have invented a certain new and useful Improvement in Automatic Charging Devices for Roasting-Furnaces and the Like, of which the following is a specification.

10 In the endeavor to charge roasting-furnaces, calcining-furnaces, drying-kilns, &c., evenly and without the aid of a laborer with materials which physically differ widely one from another, such as iron-pyrites, blende and the like, numerous charging-devices have been proposed, but hitherto none of them has succeeded in performing this operation satisfactorily. For this reason not only the furnace itself but 15 also the auxiliary apparatuses (chambers of lead, contact-furnaces etc.) are disturbed in their working and subjected to fluctuations, so that the laborer must assist again and again. The reason for this will be found 20 on the one hand in the irregular charging and on the other hand in the complicated devices employed to enforce a uniform charging of the furnace. In addition to 25 this endeavors are made to regulate the volume of the charge introduced into the furnace per unit of time whereby the uncertainty of the working of the furnace is made worse still. The present invention prevents 30 these drawbacks by exchangeably arranging 35 charging-vessels in the crown of the furnace in such a manner, that said vessels may be filled with charging-material by means of a rake attached to the rotary furnace-shaft and emptied by the aid of a false bottom 40 which is concentrically attached to said furnace-shaft to rotate within the top-story of the furnace in close proximity to the lower end of said charging-vessels. To this end the latter are made bottomless and said false 45 bottom is provided with one or more discharge-openings arranged on a circle coinciding with the circle on which the charging-vessels are arranged in the crown of the furnace, so that the vessels can be charged 50 when a solid portion of said false bottom closes their lower end, and emptied when a discharge-opening registers therewith. The variation of the volume of the charge to be 55 introduced into the furnace per unit of time by the aid of said bottomless charging-vessels is accomplished in a very simple

manner by employing charging-vessels of the same length but of a greater or lesser free cross-sectional area, as circumstances may demand it. By the aid of these simple means not only the volume of the charge 60 may be exactly regulated, but it is also made possible to fill and empty said charging-vessels most regularly and without the aid of a laborer, because the new charging-device 65 operates automatically. Since the charge can thus be exactly fixed in accordance with the kind and quality of the material under consideration a uniform operation of the furnace and of the auxiliary apparatuses is 70 assured.

In the accompanying drawing:—Figure 1 is a longitudinal sectional-view of the upper part of a roasting-furnace provided with my new charging-device. Fig. 2 is a 75 plan-view of said roasting-furnace. Fig. 3 is a plan-view of one half of the false-bottom, and Figs. 4 and 5 are details of construction on a larger scale.

In the crown 1 of the furnace 2 a facing-ring 3 is arranged for the reception of the cover-plate 4. Through the central opening 5 of this plate the tubular furnace-shaft 6 passes upward and is guided in said plate by means of the annular flange 7. Concentrically to the latter, an annular wall 8 is erected to form an annular space around the shaft 6 for sealing-material, such as sand and the like, into which the downwardly directed flange 9 dips to form a seal in order to retain the heat and gases in the upper story 10 of said furnace. The flange 9 may form an integral part of the ring 11 seated upon the shaft 6 or it may be secured thereto in any suitable manner. The cover-plate 4 is provided with a plurality of openings 12 for the reception of bottomless charging-vessels 13, which are exchangeably seated in 80 said plate. To make the top of said charging-vessels flush with the top-face of said cover-plate each opening 12 is encircled at the underside of the cover-plate by a lip 14, on which rest lateral wings 15 of the charging-vessels (Fig. 4). Since it is 85 desirable to prevent the charging-vessels from rising during the charging-operation, wings 16 are provided on the cover-plate 4 which project into each opening 12 in such a manner that when the charging-vessel is introduced into said opening and rotated until 90 the wings 15 are covered by the wings 16 the charging-vessel is securely held down. When 95 100 105 110

the roasting-material is finely comminuted the simpler way of suspending the charging-vessels illustrated in Fig. 5 will do, but where this is not the case, the above-described construction is to be preferred. The 5 tendency of the charging-vessels to rise is caused by the friction the lower parts of the charge contained in the vessels create on the tread 19, and in consequence thereof try to pass out between the tread 19 and the lower vessel-rim. The charging-vessels may 10 consist of iron, chamotte or of any other substance adapted to withstand high temperatures. The vessels are preferably closed at 15 their lower end by a false bottom 17 consisting here of two halves to simplify securing it to the shaft 6 by means of the screws 18. The tread 19 of said false bottom is provided with one or more discharge-openings 20 arranged equidistant with the charging vessels from the axis of rotation of the shaft 6. Above the crown of the furnace the 25 rake 21 is secured to the shaft 6 for sweeping the roasting-material into said charging-vessels.

The operation is as follows:—After the volume of the charge to be introduced into the furnace per unit of time has been decided upon, charging-vessels of a suitable 30 free cross-sectional area are inserted into the openings 12 and then filled with roasting-material by means of the rake 21. To this end the wedge-shaped teeth 22 of said rake are arranged in such a manner as to move 35 the material toward the center of the furnace when the shaft 6 rotates in the direction of the arrow. Since the arms of the rake 21 are related to the discharge-opening or discharge-openings 20 to prevent that the 40 charging and emptying of said vessels cannot take place simultaneously, it follows, that the roasting-material cannot pass directly through said charging-vessel into the top-story 10, but is retained by said vessels 45 until a discharge-opening registers with the lower end thereof. At the moment this takes place, the roasting-material drops into the top-story and is spread out and moved 50 in the usual manner toward the opening 23 of the partition-wall 24 by the aid of the rake 25 likewise secured to the shaft 6. In order to prevent the escape of heat and gases 55 between emptying and refilling said vessels, each vessel may be provided with a loose sleeve 26, which prevents heat and gases from passing between the lower vessel-end and the tread 19 into the charging-vessels 13, and thence into the atmosphere. These sleeves also prevent that charging-material 60 accumulates on said false bottom, since it follows any unevenness in the tread 19 which may have been caused by warping through the heat of the furnace. After a charging-vessel has discharged its contents into the 65 furnace the advancing tread 19 closes the

lower end of the vessel again, so that it can take up a new supply of charging-material.

When it is desirable to introduce greater or lesser quantities of roasting material into the roasting-furnace per unit of time than hitherto, the charging-vessels in use until now are removed and replaced by others, the cubical contents of which are adapted to fulfill the new conditions, whereby the revolutions of the furnace-shaft have to be taken into account too. Instead of giving the charging-vessels a cylindrical shape, any other shape might be employed, but from a practical point of view this is not advisable. For a similar reason it would be unadvantageous to employ any of the known conical or ball-shaped closing-means operated by springs or counter-weights instead of the simple false bottom, since such means require a constant attendance and cause frequent interruptions of the working of the roasting-plant.

I claim:—

1. An automatic charging-device for roasting-furnaces and the like, comprising a plurality of bottomless exchangeable charging-vessels and a rotatable false bottom provided with a discharge-opening adapted to register successively with the lower end of each of said charging-vessels.

2. An automatic charging-device for roasting-furnaces and the like having a shaft, a plurality of bottomless exchangeable charging-vessels arranged in the crown of the furnace equidistant from the shaft, and a false bottom rotating in the top-story of said furnace in close proximity to the lower end of said charging-vessels and provided with a discharge-opening adapted to register in succession with the lower end of each of said charging-vessels.

3. An automatic charging-device for roasting-furnaces and the like, comprising a plurality of bottomless charging-vessels exchangeably arranged in the crown of the furnace, means for preventing the rise of said charging-vessels, a false bottom continually rotating in the same direction in the top-story of said charging-vessels and provided with a discharge-opening adapted to register successively with the lower end of each of said charging-vessels, and yielding means for keeping said charging-vessels in contact with said false-bottom.

4. An automatic charging-device for roasting-furnaces and the like, comprising a cover-plate arranged in the crown of the furnace, a plurality of bottomless charging-vessels exchangeably sustained by said cover-plate, means to prevent rising of said charging-vessels, a false bottom arranged within the top-story of said furnace beneath said charging-vessels and provided with discharge-openings adapted to register successively with the lower end of each of said

charging-vessels, and an extension-sleeve loosely arranged upon the lower end of each charging-vessel.

5. An automatic charging device for roasting-furnaces and the like, comprising in combination a cover-plate arranged in the crown of the furnace, a plurality of bottomless charging-vessels exchangeably seated in said cover-plate, locking means 10 preventing the rise of said charging-vessels, a rotary shaft projecting upward through said cover-plate, a false bottom rotated by said shaft and provided with a discharge-opening adapted to register successively with the lower end of each of said charging-vessels, an extension-sleeve encircling the lower end of each charging-vessel and sustained by said false bottom, and a rake attached above said cover-plate to 15 said shaft and adapted to sweep roasting-material from said furnace-crown into said charging-vessels.

6. An automatic charging-device for roasting-furnaces and the like, comprising 20 in combination a centrally perforated cover-

plate arranged in the crown of the furnace, a plurality of bottomless charging-vessels exchangeably seated in said cover-plate, in-charging-vessels, a rotary furnace-shaft 30 charging-vessels, a rotary furnace-shaft passing centrally through said cover-plate, a seal on said cover-plate adapted to prevent the exit of heat and gases from said furnace, a false bottom secured within the top-story of said furnace to said furnace-shaft and provided with a discharge-opening 35 adapted to register successively with the lower end of each of said charging-vessels, an extension-member encircling the lower end of each charging-vessel and sliding on the tread of said false-bottom, and a rake secured to said furnace-shaft above said seal to sweep roasting-material into 40 said charging-vessels.

Signed by me at Barnmen this 8th day of 45
March 1913.
